UNITED STATES PATENT OFFICE.

ROBERT S. COOPER, OF KENOSHA, WISCONSIN, ASSIGNOR TO HENRY S. COOPER AND HORACE G. JOHNSON, BOTH OF KENOSHA, WISCONSIN.

UNDERWEAR.

1,106,133.

Specification of Letters Patent.

Patented Aug. 4, 1914.

Application filed September 13, 1911. Serial No. 649,135.

To all whom it may concern:

Be it known that I, ROBERT S. COOPER, a citizen of the United States of America, and resident of Kenosha, Kenosha county, Wisconsin, have invented a certain new and useful Improvement in Underwear, of which the following is a specification.

My invention relates to union suit underwear of the kind in which a permanently closed crotch is employed. In a union suit of this kind, made of knitted fabric, the front opening has extended downward to a point a short distance above the crotch, leaving an integral or uncut portion of the fabric between the crotch and the lower end of said opening. With this integral or uncut portion of the fabric, it was difficult to complete the work at the lower end of said front opening, as it was necessary to do this in a manner that involved an extra or special operation. Thus the cost of manufacture was increased, as the special operation, which was necessary in finishing the lower end of the front opening, involved more time and labor.

The object of my invention is, therefore, to provide a process of manufacture and a construction of such character that a garment of this kind, having a permanently closed crotch, may be made without the necessity of employing extra or special operations in finishing off the lower end of the front opening, and whereby the work may be completed by one operation on a sewing machine, in a convenient and satisfactory manner, thus reducing the cost of manufacture, as will hereinafter more fully appear.

To these and other useful ends, my invention consists in matters hereinafter set forth and claimed.

In the accompanying drawings—Figure 1 is a view showing the usual knitted tube or cylinder from which the body of the suit of union underwear is fashioned or made. Fig. 2 shows the tube or cylinder cut and shaped for sewing. Fig. 3 is a front view of the finished suit of underwear. Fig. 4 is an enlarged and fragmentary perspective view of the lower end portion of the front opening, showing the opening unbuittoned. Fig. 5 is a similar view, but showing the appearance of the parts before the final stitching is done. Fig. 6 is a vertical section of the portion shown in Fig. 4, showing the opening buttoned up.

As thus illustrated, my improved process or method of making the union suit underwear embodying the principles of my invention is as follows: First, a tube or cylinder of fabric is knitted, as shown in Fig. 1. Then the said tube is split or cut at the bottom, to provide legs 1—1, as shown in Fig. 2; the top is cut out in the usual manner for the neck, and the arm holes are made; and the front is cut or slit vertically from the neck to the crotch, so that the whole front of the tube is open. This vertical slit or cut 2 does not, it will be seen, terminate short of the crotch, but instead extends into the cut made for the legs. After this, the inner edges of the portions 1 are sewed or stitched to form the legs; the arms are sewed in, the other portions completed, and the neck finished, in the manner shown in Fig. 3. In a garment of this kind it is common to provide a posterior opening, of suitable character, and in this connection a crotch gusset or gore 3 is ordinarily sewed in place in the well known manner. If a flap is provided for the posterior opening, the portion 3 may be an integral portion of said flap. This results in a seam 4 which runs across the front of the crotch and down each leg until it joins the in-seam thereof. The vertical portion 5 at one side of the opening 2 is provided on both surfaces with a facing 6 of suitable cloth, and the buttons 7 are sewed in place thereon. The portion 8 at the other side of said opening is provided with a wide facing 9 on only the inner surface thereof, and with the usual button-holes 10. In each case the facing is sewed in place by sewing or stitching it on a sewing machine. The lower ends of the portions 5 and 8, and the facing thereof, are united at the seam 4, on a sewing machine, and are also sewed together at a point a short distance above the said seam, as by a short line of stitching 11. If desired, this stitching 11 may be omitted, although by its use the seam 4 is relieved of some strain, and the garment rendered stronger. This is all straight work and can be done easily on a sewing machine. The portions 5 and 8 lap sufficiently to bring the buttons into line with the button-holes. Thus a union suit is made with a permanently closed crotch, without the necessity of employing any extra or special operations in finishing off the lower end of the front opening, as

was formally the case when the slit 2 made in the tube of knitted fabric was made to terminate short of the seam 4 in the crotch. In this way the cost of manufacture is reduced, and the article itself rendered stronger and more satisfactory in character.

When the garment is made of knitted fabric, as shown, a button stay is inclosed in the facing, in the usual and well known manner. This button stay is, however, like the facing and fabric, terminated and fastened in place in the seam 4, so that no extra operation is required in completing the work at the lower end of the front opening. This is largely by reason of the fact that the stitching by which the facing is secured along the edges of the front opening can be carried through to the lower edges of the fabric—that is to say, to the edges that are joined to the crotch at the seam 4, in the manner explained. Previously, this stitching was carried down to a certain point, but from there down another and special operation on a sewing machine was necessary. With my improved process, however, this extra operation is eliminated, and the facing is secured in place by one continuous sewing operation.

By a permanently closed crotch, I mean one in which the crotch is entirely closed, or

substantially so, throughout the area thereof, at both front and rear of the garment.

What I claim as my invention is:

An undergarment having both legs permanently united to each other through the crotch by a gorepiece or gusset insert extending uninterruptedly from leg to leg through the crotch, the front edge of which gorepiece is joined to the front of the body of the garment by a sewed seam which extends continuously without interruption from the inside of one leg up across the front of the crotch region and down the inside of the other leg, and said garment provided with front fly members, having finished edges, and extending from the upper part of the garment down to the front edge of said gorepiece, the lower ends of said fly members being overlapped at the front edge of the gorepiece and sewed thereto by, and within, the same uninterrupted seam which unites said gorepiece to the body across the front crotch region.

Signed by me at Kenosha, Wisconsin, this 5th day of September, 1911.

ROBERT S. COOPER.
